Fig. 15

FIG. 1 is a perspective view of an expansion anchor showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a perspective view of a modified form of an expansion anchor of my invention;

FIG. 7 is a right side elevational view of the form of invention illustrated in FIG. 6;

FIG. 8 is a left side elevational view of the form of invention illustrated in FIG. 6;

FIG. 9 is a front elevational view of the form of invention illustrated in FIG. 6;

FIG. 10 is a rear elevational view of the form of invention illustrated in FIG. 6;

FIG. 11 is a perspective view of a modified form of the present invention;

FIG. 12 is a right side elevational view of the form of invention illustrated in FIG. 11;

FIG. 13 is a left side elevational view of the form of invention illustrated in FIG. 11;

FIG. 14 is a front elevational view of the form of invention illustrated in FIG. 11;

FIG. 15 is a rear elevational view of the form of invention illustrated in FIG. 11;

FIG. 16 is a modified form of the invention illustrated in FIG. 6, and

FIG. 17 is a front elevational view of the form of invention illustrated in FIG. 16.

The sides and end of the modified form of FIG. 16 not shown are similar to FIGS. 7, 8 and 9.

I claim:

The ornamental design for an expansion anchor, as shown and described.
